(57)

CLAIM

The ornamental design for a control panel, as shown and described.

DESCRIPTION

FIG. 1 shows a front perspective view of a control panel.

FIG. 2 shows a front elevation view of the control panel.

FIG. 3 shows a top view of the control panel.

(Continued)

FIG. 4 shows a bottom view of the control panel.
FIG. 5 shows a left side view of the control panel; and,
FIG. 6 shows a right side view of the control panel.
The broken line portion of the figure drawings is included to
show unclaimed subject matter only and forms no part of the
claimed design.

1 Claim, 4 Drawing Sheets
